UNITED STATES PATENT OFFICE

VICTOR ODQUIST, OF YONKERS, NEW YORK, ASSIGNOR TO AMERICAN CAN COMPANY, OF NEW YORK, N. Y., A CORPORATION OF NEW JERSEY

HINGE AND METHOD OF MAKING IT

Application filed August 1, 1927. Serial No. 209,768.

This invention relates in general to hinge construction between sheet metal parts, and while the invention will be hereinafter described as embodied in a hinge construction for connecting a sheet metal glass carrying frame for cracker cans, caddies and the like, to the body or other box part, it will be apparent that the invention has other and more general application.

10 A principal object of the invention is the provision of an improved hinge construction between sheet metal parts, which will enable the provision of an effective, durable hinge, without the use of solder or other fastening

15 medium, and/or other fastening devices.

In the marketing of crackers, biscuits, cakes, and the like, it is frequently the custom to pack the product in relatively large rectangular boxes of heavy cardboard, and to 20 supply the retail dealer with an attractive sheet metal top adapted to slip over the cardboard box body, this top being provided with a glass carrying hinge lid which protects the contents against dust, flies, and the like, in 25 the store. The material of the top is relatively light and resembles in all general respects the top of the usual cracker can of commerce. It comprises a frame arranged to embrace the top of the caddy body, and a 30 flange extending inwardly to form an abutment for the hinge member itself. These tops are used repeatedly, and the hinge construction, both on this account and because of the lightness of the material, should be of 35 substantial strength.

My invention contemplates the provision of a hinge construction for this and other uses, wherein the hinge member will, by 40 reason of its construction and arrangement in the assembly material, stiffen and strengthen the top, and which may be manufactured by merely properly shaping the parts and assembling them in interhooked relation.

45 Numerous other objects and advantages of the invention will be apparent as it is better understood from the following description, which, taken in connection with the accompanying drawing, discloses a preferred embodiment thereof.

In the drawing:

Figure 1 is a plan view of a display cover to which a hinge embodying the present invention is applied;

Fig. 2 is a section illustrating the hinge as 55 taken on the line 2—2 of Fig. 1;

Fig. 3 is a section taken on the line 3—3 of Fig. 1;

Fig. 4 is a view illustrating the relation of the parts in applying the hinge; 60

Fig. 5 is a section taken on the line 5—5 of Fig. 1; and

Fig. 6 is a detail view of the hinge looking at the inside of the cover.

Although a preferred embodiment of this 65 invention is shown in connection with a display cover, it is obvious that the hinge itself, without any material changes, may be used in various types of closures and containers, it being particularly adapted for sheet metal 70 construction where one part is connected to another by a simple form of hinge.

Referring more particularly to the drawing, a display cover is illustrated which comprises a marginal frame 10 and a cover 11. 75 The frame is preferably curled at its upper and lower edges to provide a rounded edge 12 and to enclose a margin wire 13. An upper edge 14 of the frame is formed with narrow slots 15 at spaced intervals outside of the enclosed margin wire 13 which lines the inner edge of the opening through the cover frame.

The lid 11 is formed with display openings 16 and 17, in one or both of which is a glass 80 85 90 95 100 18 held in place at opposite sides of the lid by spring strips 19 hinged in the lid on pivots 20. The outer edge of the lid is also curled to enclose a margin wire 21 which may extend entirely around the lid and at the side about which the lid is to be hinged are spaced recesses 22 in the edge of the lid exposing the margin wire 21 therein for a distance substantially equal to and adjacent the slots 15 in the frame 10.

In order to connect the lid and its frame, a hinge clip 23 of flat sheet metal is folded upon itself and around the margin wire 21 with its extremities flat together, as shown in Fig. 4. This strip is substantially as wide as the length of the slot 15 in the frame 10, and

the slot is of a width to closely engage the two thicknesses of the strip which forms a hinging clip.

The hinging clips with their ends together are inserted through the slots 15 after being engaged with the margin wire 21 of the lid, and the extremities on the inside of the margin frame 10 are bent over oppositely to form curls 24 which engage the inside of the margin frame at the sides of the slots 15, thereby clinching the hinging clips tightly in place and preventing them from disengagement with the margin frame.

In order to limit the opening of the lid with respect to the frame, cooperating projections 25 and 26 are formed in the lid and frame respectively adjacent the hinges thereof, which engage when the lid is raised and limit the opening thereof.

With this construction a lid may be hinged to a frame or body by means of a hinging clip which engages suitable recesses of the lid and frame and is clinched in the frame at the side opposite the lid without the necessity of a soldering operation.

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

In a display cover, a lid having a flange and a margin wire, a frame for the lid having a flange with narrow slots in the edge parallel to and near said wire and a clip extending around the wire with its ends inserted through the slot, and curled away from each other inside of the flange on the frame and bearing against said flange by their end portions, thereby avoiding any angular bend of said ends of the clip.

VICTOR ODQUIST.
